ENGINE STARTER

John W. Fitz Gerald, Milwaukee, Wis., assignor to
 Briggs & Stratton Corporation, Milwaukee,
 Wis., a corporation of Delaware

Application August 1, 1941, Serial No. 405,019

21 Claims. (Cl. 74—7)

This invention relates to engine starters, and refers particularly to the so-called automatic type of starter wherein inertia is relied upon to effect relative rotation between a starter gear or pinion and its power driven actuator to propel the pinion to and from operative driving engagement with the flywheel of an engine to be started.

Due to the advent of oil clutches in automobiles, the use of these automatic starters has encountered a serious problem. As will be readily apparent successful operation of a starter which relies solely upon inertia to effect relative rotation between the starter gear and its actuator requires the threaded connection between these parts to run free at all times.

Where the amount of oil coming in contact with the starter mechanism can be controlled, no particular problem is encountered, but where the entire starter must operate in a bath of oil it is apparent that difficulties arise, especially under low temperature conditions. Under these conditions the oil film friction freezes the pinion to the starter shaft. Inertia, therefore, is not enough to assure the necessary relative motion between the coating screw threaded parts and as a consequence the pinion instead of moving forwardly into mesh with the ring gear merely revolves with its actuator.

This invention is, therefore, directed toward provision of simple but effective means for overcoming this objectionable possibility and insuring translation of the pinion into mesh with the ring gear even though the screw threaded parts may be stuck together by a congealed oil film.

With a view toward structural simplicity, it is a further object of this invention to utilize centrifugal force to effect the necessary relative rotation between the starter gear and its actuator.

Another object of this invention is to provide means for augmenting inertia in effecting relative rotation between the starter gear and its actuator, which depends upon no other function of the automobile or its engine and which is entirely self-contained within the starter mechanism.

More specifically, it is an object of this invention to provide a starter having a centrifugally responsive weighted member mounted on or carried by the power driven actuator to turn therewith and connected to the starter gear in such a manner that its response to centrifugal force rotates the starter gear with respect to its

actuator to propel the gear forwardly towards the ring gear.

Another object of this invention is the provision of centrifugally responsive means for retarding the retraction of the pinion to prevent objectional rebound.

Still another object of this invention is to provide a single centrifugally responsive means for advancing the pinion and also retarding its retraction.

With the above and other objects in view which will appear as the description proceeds, this invention resides in the novel construction, combination and arrangement of parts substantially as hereinafter described and more particularly defined by the appended claims, it being understood that such changes in the precise embodiment of the herein disclosed invention may be made as come within the scope of the claims.

10 The accompanying drawing illustrates one complete example of the physical embodiment of the invention constructed according to the best mode so far devised for the practical application of the principles thereof, and in which:

20 Figure 1 is a view partly in side elevation and partly in longitudinal section of an engine starter embodying this invention;

25 Figure 2 is an enlarged cross sectional view taken through Figure 1 on the plane of the line 30 2—2, and showing the parts in the normal inoperative condition of the starter;

35 Figure 3 is a view similar to Figure 2 but showing the manner in which the centrifugally responsive means functions to turn the starter with relation to its actuator; and

Figure 4 is a perspective view of the entire starter.

Referring now particularly to the accompanying drawing in which like numerals designate like parts, the numeral 5 designates a power driven drive shaft which is preferably the armature shaft of an electric motor 6 and on which the starter indicated generally by the numeral 7 is mounted.

45 The starter 7 includes a pinion or starter gear 8 movable to and from driving engagement with a ring gear 9 which as is customary is carried by the flywheel (not shown) of the engine to be started.

The starter gear or pinion 8 has a cylindrical extension 10 projecting therefrom. This extension is internally threaded to fit a threaded actuator 11 loosely mounted on the shaft 5.

50 The actuator 11 has a resilient driving connection with the shaft 5 provided by a rubber ring 12 confined between flanges 13 and 14. The for-

mer of these flanges is fixed to the screw threaded actuating member 11 and the latter has a hub 15 by which it is fixed to the drive shaft 5. A cup-shaped outer shell 16 having its open end secured to the flange 14 encloses both flanges and the rubber ring and by a medial shoulder limits motion of the flange 13 away from the flange 14. The rubber ring is thus held under pressure between the flanges to provide initial frictional driving engagement to transmit torque resiliently from the shaft to the screw threaded actuating member 11.

Hence, when the drive shaft begins to revolve, the inertia of the starter gear and its sleeve holds the same stationary while the actuator 11 revolves therein to propel the pinion forwardly into mesh with the ring gear. Forward propulsion of the pinion is limited by the engagement of a stop flange 17 on the pinion extension with the end of the shell 16 which is flanged inwardly.

Under normal conditions, inertia may be relied upon to effect the necessary relative rotation between the pinion and its actuator but if the starter must operate in conditions where it is subjected to excessive oil as in engines equipped with oil clutches, the required free running fit between the pinion sleeve and actuator cannot be maintained especially in cold weather.

Under such conditions, the oil film which is excessive congeals and must be broken to insure advance of the pinion into mesh with the ring gear. To this end, the front end 16' of the shell has a weighted centrifugally responsive lever 18 pivoted thereto as at 19. The outer weighted end of this lever is coupled to one end of a brake band 20 preferably by means of a chain link 21 engaging in a loop on the lever.

The opposite end of the brake band is connected to a fixed anchor as for instance the pivot 19 by means of a tension spring 22. Hence, when the starter is stationary these parts assume the positions illustrated in Figure 2. However, when the starter begins to operate and the weighted lever 18 responds to centrifugal force and swings outwardly as shown in Figure 3, a pull is exerted on the brake band. Being wrapped about the pinion extension 10 and frictionally engaging the same, this pull on the band rotates the pinion with relation to its actuator 11. The direction of rotation is indicated by the arrow 23, and is such that forward translation of the pinion takes place.

After the engine starts and the pinion overruns the actuator, it is retracted in the normal manner but by virtue of the engagement of the brake band with the pinion sleeve the retraction of the pinion is materially slackened. In other words, the brake band imposes a drag on the pinion to reduce the speed of its rotation. This effectively prevents rebound. Moreover, when centrifugal force ceases to hold the weighted lever out and the spring 22 restores the parts to their normal positions, a turning moment is imparted to the pinion in the direction necessary to retract the same.

Hence, the means here provided for augmenting inertia to insure meshing of the starter pinion with the ring gear also has an anti-bounce function which is highly desirable.

Inasmuch as the brake band is constantly maintained under tension by the spring 22 and is wrapped about the pinion sleeve at all times, it follows that an "anti-creep" function is inherent in the structure of this invention.

This invention also makes possible a very de-

sirable reduction in weight of the pinion as inertia need not be relied upon at all for the advance of the pinion. As a consequence the probability of damage to the teeth of the pinion and rear gear during the meshing action is reduced.

What I claim as my invention is:

1. In an engine starter of the automatic mesh and demesh type, the combination with: a power driven member; and a member connected with the starter gear and threaded to said power driven member so that relative rotation between said members effects translation of the starter gear into and out of mesh with the ring gear of the engine to be started; of a centrifugally responsive device; and means actuated by the centrifugally responsive device in consequence to its response to centrifugal force for effecting the necessary relative rotation between said members to advance the starter gear toward the engine ring gear.

2. In an engine starter of the automatic mesh and demesh type having a power driven member and a starter gear member screw threaded to said power driven member: means for augmenting inertia normally relied upon for effecting relative rotation between said members as the starter begins to operate to insure advance of the starter gear, said means comprising a centrifugally responsive member revolvable with the power driven member and adapted to swing out from a normal position in response to centrifugal force; and a driving connection between said centrifugally responsive member and the starter gear member for turning the starter gear member with relation to the power driven member in the direction necessary to propel the starter gear forwardly.

3. In an engine starter, the combination with: a starter gear and power driven means having a part thereof provided with a screw threaded connection with the starter gear; centrifugally responsive means rotatable with the power driven means and having a motion transmitting connection with the starter gear rendered effective upon response of said means to centrifugal force, said centrifugally responsive means acting on the starter gear upon initial operation of the starter to augment inertia normally relied upon to effect relative rotation between the starter gear and said part of the power driven means and being operable to effect the relative rotation between the starter gear and power driven part necessary to effect propulsion of the starter gear toward operative position as the starter begins to operate.

4. In an engine starter: a starter gear movable to and from mesh with the ring gear of an engine to be started; a power driven actuator for the starter gear; a screw threaded connection between the actuator and the starter gear so that relative rotation between said parts in one direction propels the pinion forwardly into mesh with the ring gear; a weighted member pivotally mounted to revolve with the power driven actuator and to swing out on its pivotal mounting in response to centrifugal force; and means connecting said pivotal member with the starter gear and utilizing the outward swinging motion of said member to effect relative rotation between the gear and its actuator in the direction necessary to propel the pinion forwardly.

5. In an engine starter: a starter gear movable to and from mesh with the ring gear of an engine to be started; a power driven actuator for the starter gear; a screw threaded connection between the actuator and the starter gear so that

relative rotation between said parts in one direction propels the pinion forwardly into mesh with the ring gear; a weighted member pivotally mounted to revolve with the power driven actuator and to swing out on its pivotal mounting in response to centrifugal force; and a member connected with said pivoted weighted member and frictionally engaging a part of the starter gear to turn the same with relation to its actuator as the weighted member swings out in response to centrifugal force.

6. In an engine starter: a starter gear movable to and from mesh with the ring gear of an engine to be started; a power driven actuator for the starter gear; a screw threaded connection between the actuator and the starter gear so that relative rotation between said parts in one direction propels the pinion forwardly into mesh with the ring gear; a weighted member pivotally mounted to revolve with the power driven actuator and to swing out on its pivotal mounting in response to centrifugal force; and a member partially wrapped about a part on the starter gear and connected with said weighted member, said wrapped member having frictional engagement with said part of the starter gear so as to turn the same with relation to its actuator as the weighted member swings out in response to centrifugal force.

7. In an engine starter: a starter gear movable to and from mesh with the ring gear of an engine to be started; a power driven actuator for the starter gear; a screw threaded connection between the actuator and the starter gear so that relative rotation between said parts in one direction propels the pinion forwardly into mesh with the ring gear; a weighted member pivotally mounted to revolve with the power driven actuator and to swing out on its pivotal mounting in response to centrifugal force; a member partially wrapped about a part on the starter gear and connected with said weighted member, said wrapped member having frictional engagement with said part on the starter gear so as to turn the same with relation to its actuator as the weighted member swings out in response to centrifugal force; and spring means for returning said wrapped member and the weighted member to their normal positions.

8. In an engine starter: a starter gear having an internally threaded cylindrical extension; a power driven actuator screw threaded into said extension and operable upon relative rotation between it and said cylindrical extension to propel the starter gear forwardly; a part revolvable with the actuator and having a portion thereof adjacent to the cylindrical extension of the starter gear; a weighted lever pivoted to said part; and a brake band partially wrapped about the cylindrical extension of the starter gear and connected with said weighted lever to turn the starter gear with relation to the actuator in response to outward motion of the weighted lever by centrifugal force.

9. In an engine starter: a starter gear having an internally threaded cylindrical extension; a power driven actuator screw threaded into said extension and operable upon relative rotation between it and said cylindrical extension to propel the starter gear forwardly; a part revolvable with the actuator and having a portion thereof adjacent to the cylindrical extension of the starter gear; a weighted lever pivoted to said part; a brake band partially wrapped about the cylindrical extension of the starter gear and connected with said weighted lever to turn the

starter gear with relation to the actuator in response to outward motion of the weighted lever by centrifugal force; and a spring connected with said brake band for returning it and the weighted lever to their normal potentially operative positions.

10. In an engine starter: a starter gear mounted for translation to and from an operative driving position; a cylindrical extension on the starter gear; a power driven actuator having a screw threaded connection with said starter gear so that relative rotation between the actuator and the starter gear translates the starter gear to and from operative position; a brake band partially wrapped about the cylindrical extension of the gear; a yielding support for one end of the brake band; and a weighted centrifugally responsive member mounted to revolve with the power driven actuator and connected with the opposite end of the brake band to exert a pull thereon as the weighted centrifugally responsive member responds to centrifugal force to thereby effect relative rotation between the starter gear and its actuator in a direction necessary to propel the starter gear forwardly toward operative position.

11. In an engine starter: power driven means including an actuating member; a starter gear connected with the actuating member so as to be moved into engagement with a member of an engine to be started in consequence to relative rotation between the starter gear and actuating member; and centrifugally responsive means energized by rotation of the actuating member and connected with the starter gear so that response of said means to centrifugal force effects relative rotation between the starter gear and the actuating member.

12. In an engine starter: a motor driven starter shaft; a pinion movable along the shaft into engagement with a member of an engine to be started; a driving connection between the pinion and said shaft operable to propel the pinion along the shaft into mesh with the ring gear of an engine to be started upon relative rotation between the pinion and the starter shaft; and centrifugally responsive means having a motion transmitting connection with the pinion operable upon response of said means to centrifugal force to insure relative rotation between the pinion and the starter shaft.

13. In an engine starter: a pinion movable longitudinally to and from an operative driving position; power driven means including an actuating member; a screw threaded connection between the actuating member and the pinion whereby relative rotation between said parts effects longitudinal movement of the pinion; and centrifugally responsive means revolvable with the power driven means and operable on the pinion to effect relative rotation between said parts in a direction to advance the pinion.

14. In an engine starter: power driven means including an actuating member; a starter gear member; a threaded connection between said members whereby relative rotation therebetween effects translation of the starter gear member from and to a retracted position; and centrifugally responsive means carried by said power driven means and acting on the starter gear member throughout substantially its entire retraction to retard such retraction and thus prevent rebound of the starter gear member from its retracted position.

15. In an engine starter: a power driven means including an actuating member; a starter gear connected with the actuating member and mov-

able endwise thereby to and from an operative driving position engaging a member of an engine to be started; and a single centrifugally responsive means operable to effect endwise motion of the starter gear toward its operative driving position and to retard retraction of the gear to prevent rebound.

16. In an engine starter: a power driven member; a pinion; a threaded connection between the pinion and said power driven member whereby relative rotation between said parts effects translation of the pinion to and from an operative driving position; a centrifugally responsive member revoluble with the actuating member; and means connecting said centrifugally responsive member with the pinion whereby response of said centrifugally responsive member revolves the pinion with relation to the actuating member to propel the pinion toward operative position and whereby retraction of the pinion is retarded.

17. In an engine starter: power driven means including an actuating member; a pinion having a threaded sleeve; a threaded connection between the pinion sleeve and said actuating member whereby relative rotation between said parts effects translation of the pinion to and from an operative driving position; a centrifugally responsive member revoluble with the power driven means; and a brake band connected with the centrifugally responsive member and wrapped about the pinion sleeve whereby the pinion sleeve is revolved relative to the actuating member during operation of the starter to propel the pinion to its operative position and whereby retraction of the pinion is retarded.

18. In an engine starter having a pinion member and power driven means including an actuating member to which the pinion member is threaded so that relative rotation of said members effects translation of the pinion member from a retracted to an operative position and vice versa depending upon the direction of relative rotation; and centrifugally responsive means

carried by said power driven means and operable on the pinion member to retard translation of said pinion member from operative position to retracted position.

5 19. In an engine starter: a power driven member; a pinion having a threaded sleeve; a threaded connection between the pinion sleeve and said power driven member whereby relative rotation between said parts effects translation of the pinion to and from an operative driving position; a brake band wrapped about the pinion sleeve; and means connected with the power driven member and maintaining the brake band in tension and frictionally engaged with said pinion sleeve.

10 20. In an engine starter: a power driven member; a pinion; a cylindrical member fixed with relation to the pinion; a threaded connection between the pinion and the power driven member whereby relative rotation between said parts

20 effects translation of the pinion to and from an operative driving position; a centrifugally responsive member revoluble with the power driven member; a brake band having one end connected with the centrifugally responsive member and wrapped about the cylindrical member; and means connected with the opposite end of the brake band for maintaining the brake band in tension and frictionally engaged with said cylindrical member.

30 21. In an engine starter of the type wherein a pinion is automatically propelled to and from an operative driving position by relative rotation between a nut and screw: a power driven shaft on which the starter is mounted; centrifugally responsive means at all times rotatable with the shaft; and means actuated by the centrifugally responsive means and operable to effect relative rotation between the nut and screw in the direction necessary to propel the pinion toward its operative driving position.

JOHN W. FITZ GERALD.
